US0D1036920S

(12) **United States Design Patent** (10) Patent No.: **US D1,036,920 S**
(45) Date of Patent: ** Jul. 30, 2024

(54) **PRESSURE COOKER**

- (71) Applicant: **FOSHAN SHUNDE MIDEA ELECTRICAL HEATING APPLIANCES MANUFACTURING CO., LTD.**, Foshan (CN)
- (72) Inventors: **Yuxin Cao**, Guangdong (CN); **Huiming Wu**, Guangdong (CN); **Jie Ding**, Guangdong (CN); **Guanhong Ru**, Guangdong (CN)
- (73) Assignee: **FOSHAN SHUNDE MIDEA ELECTRICAL HEATING APPLIANCES MANUFACTURING CO., LTD.**, Foshan (CN)

(**) Term: **15 Years**

(21) Appl. No.: **35/517,267**

(22) Filed: **May 26, 2022**

(80) **Hague Agreement Data**

Int. Filing Date: **May 26, 2022**
Int. Reg. No.: **DM/221365**
Int. Reg. Date: **May 26, 2022**
Int. Reg. Pub. Date: **May 26, 2023**

(30) **Foreign Application Priority Data**

- Dec. 7, 2021 (CN) 202130807218.9
- (51) **LOC (14) Cl.** **07-02**
- (52) **U.S. Cl.**
USPC **D7/358**; D7/323; D7/354
- (58) **Field of Classification Search**
USPC D7/320, 323, 325, 339, 346, 347, 354,
D7/355, 356, 358
CPC A21B 1/06; A21B 1/50; A21B 1/52; A23L
7/161; A47J 45/074; A47J 27/00; A47J
27/004; A47J 27/08; A47J 27/0802
